UNITED STATES PATENT OFFICE.

GAVIN J. LANG, OF DES MOINES, IOWA.

SHINGLING-GAGE.

1,291,558.

Specification of Letters Patent.

Patented Jan. 14, 1919.

Application filed April 24, 1917. Serial No. 164,210.

To all whom it may concern:

Be it known that I, GAVIN J. LANG, a citizen of the United States, residing at Des Moines, in the county of Polk and State of 5 Iowa, have invented certain new and useful Improvements in Shingling-Gages, of which the following is a specification.

This invention relates to gages, and particularly to gages for use in connection with 10 carpenter tools.

The primary object of the invention is to provide a gage for use in shingling, and the improved gage is constructed so as to be assembled upon a shingling hatchet or driving 15 tool, whereby the distances between the exposed edges of the shingles may be accurately determined without resorting to the use of a tool other than the driving instrument itself.

20 Still further objects reside in providing a gage capable of being quickly and easily applied to or adjusted upon the driving tool, which is composed of but few extremely simple and inexpensive parts, all of which are 25 so constructed and assembled as to minimize the opportunity for derangement of the same, and which will prove highly efficient and practical in use.

With these objects in view together with 30 others which will appear as the description proceeds, the invention resides in the novel formation, combination, and arrangement of parts, all as will be described more fully hereinafter, illustrated in the drawings, and 35 particularly pointed out in the claim.

In the drawings—

Figure 1 is a side elevation of a conventional form of shingling hatchet or driving tool, and illustrating the application thereto 40 of a gage constructed in accordance with the invention;

Fig. 2 is a perspective view of the improved gage removed from the driving tool; and

45 Fig. 3 is a detail perspective view of the gage-holding clip or cleat employed in carrying out the invention.

Referring now to the drawings, 5 indicates the head and 6 the handle of a conventional 50 form of hatchet, preferably of that type used by carpenters or builders for shingling. The handle, as is well known, extends through and is anchored in the head.

The gage includes a stem or rod 7, to one 55 end of which is secured a gage disk 8, the latter having a notch 9 opening in from one

edge thereof. This rod is adapted to lie close upon the front edge of the hatchet, and the notch 9 is adapted to inclose the front edge of the tool, so as to hold the gage disk 60 against movement laterally of the said tool edge. The upper portion of the rod or stem 7 may be confined within a groove or channel 10 disposed laterally of a retaining clip or plate 11, the latter being held firmly to 65 the tool by a screw 12. The screw may be driven into the wood of the handle which terminates usually flush with the forward edge of the tool, and it will be understood that when the screw 12 is tightly applied to 70 the said handle portion, the plate 11 will firmly clamp the rod 7 in proper position upon the tool edge. Should it be desired to vary the distance between the gage disk 8 and the driving surface of the tool, it is but 75 necessary to loosen the screw 12.

In operation, the gage is applied to the tool in the manner stated, and the gage disk is spaced from the driving surface of the tool a distance equal to that for which it is desired 80 the shingles are to be exposed. After the first or bottom layer of shingles have been applied, the tool is laid upon the said bottom row and moved upwardly until the protruding edge of the disk 8 engages the 85 lower edge of the shingle. The shingle to be laid upon the first-mentioned row may then be applied to the roof and moved downwardly until the lower edge of the same rests upon the driving surface of the tool. 90 When so positioned, the edges of the first and second shingles will be spaced apart the required distance, and the tool may then be employed in driving the nails into the shingle to firmly secure the same to the roof. It 95 is thus seen that I have provided an extremely simple gage for accurately determining the proper location of the various shingle rows, and by the use of an instrument of this character the uneven laying of 100 shingles is obviated.

While the present is a disclosure of what is believed to be the preferred embodiment of the invention, it is to be understood that the invention is not limited thereto but that 105 various changes in the minor details of construction, proportion, and arrangement of parts may be resorted to without departing from the spirit of the invention as defined in the appended claim.

110 What is claimed is:—

The combination with a hatchet having a

blade provided with a straight edge, of a clip comprising a plate having a groove in its under face and extending throughout the length thereof, a screw for holding said clip directly upon the handle portion of said hatchet with the groove parallel to the said straight edge, a gage rod adapted to be enclosed by said groove and to be forced by said clip into engagement with the said straight edge, and a gage disk rigidly secured on one end of said rod and having a

notch for engagement with the straight edge, the said screw being adapted to bind the clip and gage rod firmly upon the said handle portion and straight edge. 15

In testimony whereof I affix my signature in presence of two witnesses.

GAVIN J. LANG.
